UNITED STATES PATENT OFFICE.

JAMES E. KENNEDY, OF WASHINGTON, DISTRICT OF COLUMBIA.

GAS-CONTROLLING DEVICE FOR STOVES.

1,182,383.

Specification of Letters Patent.

Patented May 9, 1916.

Application filed December 9, 1914. Serial No. 876,296.

To all whom it may concern:

Be it known that I, JAMES E. KENNEDY, a citizen of the United States of America, residing at Washington, District of Columbia, have invented certain new and useful Improvements in Gas-Controlling Devices for Stoves, of which the following is a specification.

This invention relates to gas controlling devices for stoves, particularly gas ranges and the like, the primary object of the invention in its broad aspect being to provide a device whereby the supply of gas to the burner and the ignition thereof at the burner will be controlled by placing a vessel upon, or removing same from the stove.

The invention is an improvement upon that shown, described and claimed in Letters Patent 1,070,812 granted to me August 19, 1913 and Letters Patent No. 1,151,108, granted to me August 24, 1915, the primary object of the present invention as distinguished from the invention disclosed in the aforesaid Letters Patent is the provision of means for controlling the supply of gas through mechanism operated by the placing of a vessel upon, or removal from the stove, without imparting any movement to the pilot light tube, to obviate any danger of extinguishing of the pilot light when the mechanism is operated.

A further object of the present invention is to provide in juxtaposition to the burner cock, a regulating valve for the pilot light by means of which the amount of gas admitted to the pilot light tube can be varied at will, and, when desired, a sufficient amount of gas admitted to such tube or pipe as to permit of utilizing of the pilot light as a "simmer" burner, obviating the necessity of providing a separate burner for this purpose on the stove.

Another object is the provision of a filtering medium for the pilot light tube for purifying the gas before the same reaches the tip by absorbing from the gas any moisture or foreign matter, the filtering medium in the present invention being located at a point remote from the flame and consequently not subjected to the heat of the latter, thus protecting the filtering medium for rapid deterioration. The location of the filtering medium moreover provides for easy renewing of the same when necessary.

A still further object of the present invention is to so mount the pilot light tip upon the pilot light tube as to permit of its being readily moved or adjusted to bring it into the desired proximity with relation to the burner proper, without necessitating any change or alteration in the position of the pilot light tube itself.

Other minor objects are sought by the present invention, all of which will be hereinafter more specifically described and then claimed, without however confining myself to the precise construction shown and described, as various slight changes may be made in the details of construction without departing from the general spirit thereof and the scope of the same as claimed.

In describing the invention in detail, reference will be had to the accompanying drawings illustrating a practical and preferred embodiment of the invention, like numerals of reference indicating like parts throughout the different views, in which:

Figure 1 is a fragmentary vertical sectional view taken through a gas stove showing my invention applied thereto. Fig. 2 is a bottom plan view of the same. Fig. 3 is a detail perspective view on an enlarged scale of a portion of the pilot light tube and the adjustable bracket which slides on said tube, also showing a portion of the operating lever for the bracket. Fig. 4 is a transverse vertical sectional view through the bracket shown in Fig. 3 and the pilot light tube, the operating lever for the bracket being shown in side elevation. Fig. 5 is a central longitudinal sectional view through the filtering medium holder with which the pilot light tube is connected, showing a part of the coupling that connects same to the gas controlling cock. Figs. 6 and 7 are detail views in side elevation of the pilot light tube coupling partly broken away, the regulating valve of such coupling being in transverse section, Fig. 6 showing the valve in fully opened position, and Fig. 7 showing the valve in closed position, and Fig. 8 is an enlarged sectional view through the valve mechanism.

In the devices shown in the Letters Patent referred to, the pilot light tube is connected at its rear end with the gas controlling cock, and intermediate its ends has connection with the mechanism that is operated by the placing upon, or removal of a vessel from

the stove, so that a reciprocatory or back and forth movement is imparted to the pilot light tube, the tube being moved in one direction when a vessel is placed upon the 5 stove, and in the reverse direction when the vessel is removed. While the mechanism above set forth broadly has been found highly practical and efficient in daily use, it has been found that where the movement 10 imparted to the pilot light tube was exceedingly rapid, or in instances where the pilot light flame was very small, some danger exists of the pilot light being extinguished due to its rapid movement through 15 the air. Furthermore, where the pilot light flame is quite small and for this reason not plainly visible at the pilot light tip, the operator is sometimes in doubt whether the pilot light is extinguished or not, necessitating 20 a manipulation of the mechanism to determine such fact.

Those parts of the present device which are the same in construction as in the aforesaid patents it is not deemed necessary to 25 describe in detail herein, and the same will therefore be described only generally.

In the present illustration 10 indicates generally, a stove embodying an upper or top plate 11 provided with apertures in 30 which are mounted the usual grids 12, below each of which is a gas burner 14 supplied with gas through a burner pipe 15 fed from a supply pipe 16 in the usual manner, it being understood that for each gas burner 35 14 and burner pipe 15 employed, a separate or individual controlling cock 17 is provided. The valve member 18 of the controlling cock 17 employed in the present invention is of the same construction as is 40 fully shown and described in Letters Patent 1,070,812 heretofore referred to, which provides for a flow of gas from the supply pipe 16 to the burner pipe 15 and burner 14 when the valve is in open position, and 45 which prevents the gas from so flowing to the burner when the valve is in closed position, the valve 18 however being so arranged and constructed that a constant supply of gas from the supply pipe 16 to the pilot tube 50 is provided unless the passage way leading from the cock 17 to the pilot light tube be closed by a manually manipulated regulating valve to be hereinafter more particularly referred to. A manually operable 55 valve 19 as usual is provided for shutting off the flow of gas to the burner independently of the valve 18.

As heretofore stated, the pilot light tube in this construction remains stationary, the 60 valve 18 being operated by a member separate from the pilot light tube instead of by the latter as in my Patent No. 1,151,108. This stationary mounting of the pilot light tube enables me to dispense with the sup- 65 porting bracket necessary in the construc-

tion shown in said Patent No. 1,151,108, since such tube is comparatively light in weight and its support at its inlet end is wholly sufficient when no movement of the tube is required. This simplifies and materially cheapens the cost of manufacture.

Depending from the lower side of the casing of the cock 17 is a pipe coupling 20, closed at its lower end and the passage 21 in which communicates through passage 17' 75 in the cock casing with the gas supply pipe 16. Tapped or threadedly connected with this pipe coupling 20 at or near its lower end is a pipe 22 into the inner end of which the receiving end of the pilot light tube 23 80 is received, preferably by a threaded engagement as shown.

The purpose of providing the pipe 22 instead of connecting the outer end of the pilot light tube directly with the pipe coupling 20 is to provide a suitable receptacle for the filtering medium 24 such as cotton or the like, with which the pipe 22 is more or less filled. By locating this filtering medium in a member separate from the pilot 90 light tube and at a point remote from the zone of heat from the burner, the material is wholly removed from the action of the heat thereon, thus materially increasing the life of the filtering medium, necessitating 95 very infrequent if any renewals.

The pilot light tube is extended underneath the burner tube 15 and burner 14 and has its inner end bent upwardly within the central opening of said burner, and has mounted 100 thereon, a burner tip 25, the purpose of this particular form of tip being to provide such mixture of air and gas as to insure of a blue flame. In my Patent No. 1,122,944, December 29, 1914, the burner tip is shown as 105 threadedly-connected with the discharge end of the pilot light tube. I prefer in using this tip with the present invention to simply sleeve it onto the discharge end of the pilot light tube with a relatively tight 110 fit as this enables me to readily adjust the tip on the pilot light tube so as to bring the discharge end of such tip into any desired relation to the burner 14.

The quantity of gas permitted to flow 115 from the supply pipe 16 to the pilot light tube is controlled by a regulating-valve 26 mounted in the pipe coupling 20, and in order that the pilot light may be made to serve the purpose of the separate burner 120 oftentimes provided and known generally as a "simmer" burner, I make the passage-way 21 in the pipe coupling 20 and the port 27 in the valve 26, relatively large so as to admit a sufficient quantity of gas for the 125 purpose stated when it is desired to so make use of the pilot light tube. A pin 29 carried by the valve 26 works in a recess 30 provided therefore in the pipe coupling 20 and limits the movement of the valve in 130

both directions, as well as indicating, when at any point between the limits of its movement, the amount of opening of the valve 26.

For operating the valve 18 when a vessel 5 is placed upon the grid 12, a counterbalanced operating member 31 is employed which is described in detail in my said Patent No. 1,151,108, including a cap to be engaged by the vessel. This operating 10 member like in said Patent No. 1,151,108 has a loose connection at one end with the arm 32 of a bell-crank lever that is mounted to swing on the under side of the stove top 11. The other arm 33 of this bell-crank lever 15 instead of being formed with a head as in said Patent No. 1,151,108 terminates in a hook or clevis 34 which receives the pilot light tube 23 within a substantially U-shaped bracket 35 that is adjustably mounted 20 on a rod 36 carried by or secured to the lower end of a lever-arm 37 that is attached to the valve 18. The bracket 35 is secured in adjusted position upon the rod as by a set screw 38, binding the rod between it and 25 a flange or lug 39 carried by the bracket (see Fig. 4).

Such being the construction, the operation may be briefly stated as follows: Assuming the device to be in the position shown in 30 Fig. 1, the pilot light having been ignited, and the manually controlled valve 19 being in open position, it will be evident that when a vessel is placed upon the conical cap of the operating member 31 the depression of said 35 cap by the weight of the vessel actuates the swinging bell-crank moving the lower end of arm 33 outwardly and carrying therewith bracket 35 and rod 36 so as to operate lever-arm 37 and open the valve 18 to admit 40 gas to the burner tube 15 and burner 14 where it is ignited by the pilot light. Upon the removal of the vessel, the counterweight 40 returns the operating member to elevated position, simultaneously actuating the bell- 45 crank and rod 36 so as to close valve 18 and shut off the flow of gas to the burner, the pilot light tube remaining stationary at all times whereby the flame of such pilot light is at no time in danger of being extinguished. 50

By adjusting the position of the bracket 35 on the rod 36, and the resultant adjustment which is made to the long arm of the bell-crank, the extent to which the valve 18 55 will be opened or closed can be readily controlled to provide any desired flame at the burner.

The use of the pilot light as a "simmier" 60 burner necessitates only the closing of the valve 19 and the adjustment of valve 26 to permit the desired flow of gas into the pilot light tube, the actuation of the valve 18 by the operating member under these 65 conditions having no effect on the flow of gas.

What I claim is:

1. In combination, a burner, a gas supply, a cock between the burner and the gas supply, a controlling valve in said cock having a stem, a slidably mounted bracket, an operative connection between the bracket and valve stem, an operating member, and a connection between the bracket and operating member. 70

2. In combination, a burner, a gas supply, a cock between the burner and gas supply, a controlling valve in said cock, a pilot light tube leading from said cock and fixed beneath said burner, a bracket slidable on the pilot light tube, an operative connection 80 between the bracket and valve, an operating member, and an operative connection between the bracket and operating member. 85

3. In combination, a burner, a gas supply, a controlling valve in the cock, a lever arm carried by the valve, a slidable bracket, a rod connected to the bracket and lever arm, an operating member, and an operative connection between the bracket and the operating member. 90

4. In combination, a burner, a gas supply, a cock between the burner and gas supply, a controlling valve in said cock provided with a stem, a lever arm fixed on said stem, a rod pivoted to the lever arm, a slidably mounted 95 bracket connected to the rod, an operating member having one end fixed and the other end free and a bell crank lever having one arm connected to the bracket and the other arm connected to the free end of the operating member. 100

5. In combination, a burner, a gas supply, a cock between the burner, and gas supply, a controlling valve in said cock provided with a stem, a lever arm fixed to said stem, 105 a rod pivoted to the lever arm, a fixed pilot burner tube extending beneath the burner, a bracket slidably mounted on the tube and connected to the rod, an operating member having one end fixed and the other free, and 110 a bell crank lever having one arm connected to the bracket and the other arm connected to the free end of the operating member.

6. In combination, a burner, a gas supply, a cock for controlling the supply of 115 gas to the burner, a controlling valve in said cock, a pipe coupling with its passage in constant communication through the cock with said gas supply, a pilot light tube connected with said coupling and in communication 120 with said passage, a regulating valve in the coupling for said passage, an operating member having one end fixed and the other end free, a bracket slidably mounted on the pilot light tube, a rod connected to said 125 bracket, an arm connected to the controlling valve and rod, and a bell crank lever having one arm connected to the bracket and the other arm connected to the free end of the operating member. 130

7. In combination, a burner, a gas supply, a cock between the burner and gas supply, a controlling valve in said cock, a lever-arm carried by the cock, a rod connected to said lever-arm, a bracket adjustably mounted on said rod, an operating-member, and connections between the operating-member and bracket whereby the valve is operated simultaneously with the operating member.

8. In combination, a burner, a gas supply, a cock between the burner and gas supply, a controlling valve in said cock, a pilot light passage in the cock independent of the valve, a coupling depending from the cock and having a passage in communication

with said pilot light passage in the cock, a regulating valve for said passage in the coupling, a pilot light tube connected with the coupling, a lever-arm carried by the controlling valve, a counterbalanced operating-member, and connections between the operating-member and the lever-arm for operating the valve without affecting the pilot light tube.

In testimony whereof I affix my signature in presence of two witnesses.

JAMES E. KENNEDY.
